UNITED STATES PATENT OFFICE.

GEORGE S. STRONG, OF NEW YORK, N. Y., ASSIGNOR TO JAMES N. GAMBLE,
OF CINCINNATI, OHIO.

DEVICE FOR TRANSMITTING MOTION.

SPECIFICATION forming part of Letters Patent No. 471,656, dated March 29, 1892.

Application filed May 29, 1891. Serial No. 394,466. (No model.)

To all whom it may concern:

Be it known that I, GEORGE S. STRONG, of the city and county of New York, State of New York, have invented a certain new and useful Device for Transmitting Motion, of which the following is a true and exact description, reference being had to the accompanying drawings, which form a part of this specification.

10 My invention relates to devices for transmitting motion from one rotary body to another moving about the same axes of rotation, and particularly to devices used in connection with electric motors, the object of my 15 invention being to provide what I may call a "fluid-clutch," by which the motion of the one body is transmitted to the other, and to combine with such mechanism devices for varying the resistance offered by the fluid and an electric motor.

In another application, filed May 29, 1891, Serial No. 394,465, I have shown and described the device to which this application refers, together with a modification of the 25 same, but have not specifically claimed the particular mechanism to which this case refers.

The nature of this invention will be best understood as described in connection with 30 the drawings, in which it is illustrated, and in which—

Figure 1 is a plan view showing two axles of a truck, each equipped with my invention and partly in section. Fig. 2 is an elevation 35 of the part shown in Fig. 1, partly shown in section on the line $x-x$ of Fig. 1. Fig. 3 is a cross-sectional view taken on the line $y-y$ of Fig. 1; Fig. 4, an end view of the car-axle and the casing surrounding it and the side plate 40 of the casing removed, and it is shown partly in section on the line $z-z$ of Fig. 3; and Fig. 5 is a cross-sectional view taken through one 45 of the end plates of the casing on the line $1-2$ of Fig. 4.

A is a shaft, in the present case a car-axle, and B a gear-wheel secured to the said shaft. Around this gear-wheel is a casing consisting of two end plates c^{xx} , journaled on the shaft

by means of sleeve extensions c and bolted to a casing center c^x . 50

c', c' are glands at the ends of the sleeve C. Obviously the casing-center may, if desired, be formed integral with one of the face-plates. In the casing made up as desired a chamber c^2 is formed, which fits neatly around the gear-wheel B, and in addition to said chamber one or more supplemental chambers c^3 are formed in the casing, which chambers communicate with the chamber c^2 , as shown, and in which are situated gear-wheels D D, fitting neatly 55 within their chambers and in engagement with the teeth of wheel B. The teeth of the engaged gear-wheels are formed so that they will segregate spaces between them as they roll together, and in the face-plates and on the 60 line where the chambers c^2 and c^3 meet I form ports c^6 and c^7 , the rear portions of which communicate, as shown. The port c^6 opens into a straight passage c^5 , into which passage also the port c^7 opens at c^8 . The communication 65 between the ports is regulated by a valve E, preferably having a conical face E' , which when moved over the portion c^9 of passage c^5 closes said passage entirely and which, in intermediate positions, can be made to 70 partly close said passage. 75

The chambers c^2 and c^3 are filled with a fluid, and it will be seen that as the teeth of gears B and D roll together, the fluid enclosed between the teeth will be forced out 80 of the constantly-decreasing space, and will escape through one of the ports c^6 or c^7 into the other of said ports, from which it enters the space between the teeth as they move apart, and it will also be seen that when the 85 connection between the ports is closed, the fluid cannot escape from between the teeth of the engaged gear-wheels, and therefore the wheels cannot rotate with respect to each other, but remain locked until the communication between the ports is restored. Now if the port communication be closed by the valve and either the shaft or the casing rotated, it is obvious that the rotation of the one will be directly communicated to the 90 other, while, on the other hand, if the commun- 95

nication between the ports be open and the gears B and D permitted to rotate with respect to each other the one part of the coupler can rotate independently of the other.

5 As shown in the drawings, ports are formed opposite to each other in each face-plate of the casing, and the two valves E, controlling the communication between the ports in each face-plate, are connected with the same spindle E², which spindle is continued out through one face-plate, and secured to an annular ring M, which ring is fastened to a sleeve c of the casing, so as to rotate with it, but be free to move laterally thereupon. By moving 15 the ring to or from the casing, the valves attached to the spindles or valve-stem are simultaneously removed.

The central part of the casing is surrounded by an annular rim cored out or having 20 openings c^{xxx} between the said annular ring and the central chamber of the casing. Supported on the rim is an armature-core I³, and through the rim inside of the part supporting the core-holes I' are formed, through which 25 and holes I² in the core are passed wire-windings, as indicated at I⁴, in such manner as to convert the entire rim of the casing into an annular armature, which as a whole is indicated by the letter I.

30 Journaled upon the axle A, either directly or indirectly, and, as shown in the drawings, directly upon the sleeves c of the casing already mentioned, is a casing J, to and within which is secured the magnetic field J³ of an 35 electric motor, of which I is the armature. This casing is supported directly upon the axle or shaft A; but as it is not to rotate with the shaft, it must have another point of support to hold it stationary. This in the drawings is indicated by the brace N, connecting 40 two casings J on adjacent axles. The casing J is made as tight as practicable, in order to protect the armature and magnetic field. One opening J⁵ is formed in it, through which extends a lever L⁴, having forked ends L⁷, which 45 are attached on each side of a ring M³, surrounding the ring M, the lever being pivoted to a link L⁵, pivoted in turn on a bolt L⁶, secured to casing J. The upper end of lever 50 L⁴ is connected by a link L⁸ with a lever-arm L², extending out from shaft L, journaled in a projection J⁶ of casing J, and which shaft is actuated by another lever-arm L', from 55 which any convenient connection can be made to an operating lever or handle in convenient reach of the car-driver.

The commutator by which the current is taken from the armature is indicated at G H.

K indicates the support for the brushes, 60 which is secured to casing J, and, as shown, extends out through an opening J⁴ in said casing.

Having now described my invention, what I claim as new, and desire to secure by Letters 65 Patent, is—

1. As a device for transmitting motion, the combination of a shaft A, having a pinion B, a tight casing inclosing said pinion but free to turn on the shaft, said casing having a chamber c², fitting neatly around the pinion B, one or more communicating chambers c³ and communicating ports c⁶ c⁷, arranged along the connecting-line at the end or ends of chambers c² c³, as described, a pinion D, fitting neatly in each chamber c³, arranged to 70 engage pinion B, a valve or valves E, arranged to regulate the opening between ports c⁶ and c⁷, electro-magnetic armature-windings secured to the casing, and a relatively fixed magnetic field arranged around the casing, 80 substantially as and for the purpose specified.

2. As a device for transmitting motion, the combination of a shaft A, having a pinion B, a tight casing inclosing said pinion but free to turn on the shaft, said casing having a 85 chamber c², fitting neatly around the pinion B, one or more communicating chambers c³ and communicating ports c⁶ c⁷, arranged along the connecting-line at the end or ends of chambers c² c³, as described, a pinion D, fitting neatly in each chamber c³, arranged to 90 engage pinion B, a valve or valves E, arranged to regulate the opening between ports c⁶ and c⁷, electro-magnetic armature-windings secured to the casing, a relatively fixed magnetic field arranged around the casing, and a 95 casing for the field-magnets journaled on the shaft.

3. As a device for transmitting motion, the combination of a shaft A, having a pinion B, a tight casing inclosing said pinion but free to turn on the shaft, said casing having a chamber c², fitting neatly around the pinion B, one or more communicating chambers c³, a port c⁵ c⁶, extending at right angles from the 100 end of the connecting-line between chambers c² and c³, a port c⁷, extending from the opposite end of said connecting-line and connected with the back end of port c⁵, a pinion D, fitting in each chamber c³ and engaged with 105 pinion B, a valve-stem E², extending through port c⁵, and a valve E, secured to said stem and adapted to close and regulate port c⁵, as 110 described.

4. The combination of a shaft A, a pinion B secured thereon, a tight casing journaled on the shaft, having a chamber c³ to fit around pinion B, and chambers c² c³, communicating with the chamber c², as described, pinions D D, fitting in chambers c³ and in engagement 115 with pinion B, ports c⁶ c⁷, formed in the side lines where chambers c² and c³ communicate and connecting with each other, as described, valves E, arranged to regulate the communication between each pair of ports c⁶ c⁷, as described, valve-stems E², connecting said valves 120 in pairs and extending out through the side of the casing, a ring M, secured to a sleeve c of the casing, so as to turn with it but be free to move laterally, said ring being attached to 125 130

end of valve-stem E², and means for moving ring M, all substantially as and for the purpose specified.

5. In combination with a shaft A, having a pinion B attached to it, a casing journaled on said shaft having chambers c² c³, pinions D in chambers c³, and ports formed as described, said casing having also an annular rim and openings c^{xxxx}, formed between the rim and

central chamber c², and an electric-motor armature consisting of a core I³ and wire windings I⁴, passing through the casting, rim, and core, substantially as and for the purpose specified.
